DESIGN.

H. G. & W. R. DAWSON.
FIRE PLACE GRATE.

No. 17,401.

Patented June 21, 1887.

UNITED STATES PATENT OFFICE.

HENRY G. DAWSON AND WILLIAM R. DAWSON, OF CHICAGO, ILLINOIS.

DESIGN FOR A FIRE-PLACE GRATE.

SPECIFICATION forming part of Design No. 17,401, dated June 21, 1887.

Application filed April 23, 1887. Serial No. 235,913. Term of patent 7 years.

To all whom it may concern:

Be it known that we, HENRY G. DAWSON and WILLIAM R. DAWSON, of Chicago, Illinois, have invented and produced a new and 5 original Design for Grates for Fire-Places, of which the following is a specification, reference being had to the accompanying photographs, forming a part thereof.

Figure 1 is a front view of the back and side 10 plates detached; and Fig. 2 is a front view of the grate complete, comprising the side and back plates and the front piece.

The design consists in the raised figured work on the face of the back and side plates 15 and in the front piece, and also in the several features as a whole, the leading features being the three-headed dragon and the griffin-like figures.

A designates the side plate, and B the back 20 plate, the face of the side plate covered with raised work representing leaves, flowers, and vines, and a rectangular beaded figure, c. The lower part of the back plate is provided with raised floral work similar to the side plates, 25 and two rectangular figures, c, offsetting those of the side plates. In the center, above the rectangular figures, is the figure of a three-headed dragon, b. There is also a raised bead, c', extending from behind the dragon to the 30 vertical sides of the plate and coincident with a similar bead, c', near the top of the side plates, extending forward from the rear. The back plate is rectilinear in shape, except along a portion of the top line, which rises as a 35 mound or hill in the center over the heads of the dragon, and the top edge of the side plates

slopes from the back edge which joins the back plate in a curved slope downward toward the front. The front edge of the side plates terminates in a carved post, a, from the top of 40 which rises an ornamental flame-knob.

The front piece, C, consists of two horizontal bars in front of the fire-grate, which are held at each end by a gardant griffin, b', whose extended wing partially obscures the front posts, 45 a. The griffins rest on a bottom bar or sill, a', under the post a. The bar a' is provided with a cap, a'', on each end for post a to rest on.

What we claim, and desire to secure by Letters Patent, is—

1. The design for a fire-place grate herein shown and described, the same consisting of the side plates, A, and back plate, B, and front piece, C, having the raised figured work, three-headed dragon, and griffin-like figures, as 55 shown and described.

2. In a design for a fire place grate, as herein shown and described, the back plate, B, having the lower part of its surface provided with figured work surmounted with a three headed 60 dragon, b, as shown and described.

3. In a design for a fire-place grate, as herein shown and described, the back and side plates provided with raised work, as shown and described, and the front piece having a griffin-like figure, b', at each side, as shown. 65
